To all whom it may concern:

Be it known that I, Roger L. Nowak, a citizen of the United States, residing at West Boylston, Commonwealth of Massachusetts, have invented a new, original, and ornamental Design for a Dish or Similar Article of Hollow Ware, of which the following is a specification, reference being had to the accompanying drawing, forming part hereof.

Fig. 1 is a front elevation of a dish or similar article of hollow ware, showing my new design;

Fig. 2 is a bottom plan view of the same; and

Fig. 3 is a section taken on line 3—3 of Fig. 1, only one of the walls and a portion of the bottom of the dish being shown.

I claim:

The ornamental design for a dish or similar article of hollow ware, as shown.
